Primary Examiner — Michelle E Wilson*(74) Attorney, Agent, or Firm* — Global Intellectual Property Agency, LLC; Jordan Sworen(57) **CLAIM**

The ornamental design for a window de-icer, as shown and described.

DESCRIPTION

FIG. 1 shows a perspective view of a window de-icer showing my new design;

FIG. 2 shows a front view thereof;

FIG. 3 shows a rear view thereof;

FIG. 4 shows a right side view thereof;

FIG. 5 shows a left side view thereof;

FIG. 6 shows a top plan view thereof; and,

FIG. 7 shows a bottom plan view thereof.

The shade lines in the Figures show contour and not surface ornamentation.

The broken lines shown in the Figures show portions of the window de-icer which form no part of the claimed design.

1 Claim, 5 Drawing Sheets(56)
